UNITED STATES PATENT OFFICE.

WILLIAM L. BARNES, OF YONKERS, ASSIGNOR OF THREE-FOURTHS TO
THOMAS GEREHART, ALLEN S. GOOKIN, AND E. F. J. GAYNOR, ALL
OF NEW YORK, N. Y.

SHIELD AND BINDER FOR BRUSHES.

SPECIFICATION forming part of Letters Patent No. 355,120, dated December 28, 1886.

Application filed October 22, 1885. Serial No. 180,625. (Model.)

To all whom it may concern:

Be it known that I, WILLIAM L. BARNES, of Yonkers, in the State of New York, have invented a new and useful Improvement in Brush-Bridles; and I do hereby declare that the following is a full, clear, and exact description thereof,

My invention relates to those devices which are employed to shield and bind brushes, particularly paint-brushes, both before and during use; and it consists in the construction and combination of parts hereinafter described, and particularly pointed out in the claims.

Heretofore, so far as I am aware, brush-bridles have been formed of rubber, which could be turned up as the brush was worn away, or of thin metal bands or cylinders, adjustably attached to the stock or handle of the brush by means of slides, springs, pins, screws, &c.

The object of the present invention is to produce a bridle, which shall have the simplicity of the rubber bridles, while possessing even greater durability and effectiveness than the ordinary metal bridles.

In the accompanying drawings, forming part of this specification, Figure 1 represents a side view of an ordinary paint-brush with my improved bridle applied thereto. Fig. 2 represents on a larger scale an elevation and a plan view of one part, and Fig. 3 represents like views of the other part of my improved bridle.

The bridle may be made of sheet metal—such as zinc or other like material—and consists, as shown, of two telescopic sections. The shield or upper section, *a*, is of size and shape to fit snugly around the stock of the brush, and to project for a portion of its length below the stock. The lower edge is turned in to form a narrow flange, *e*, and two lugs or projections, *d*, of size and thickness relative to the shield and its flange, as indicated in Fig. 2, are soldered or otherwise secured to the inner walls of the shield, near its lower edge, and diametrically opposite each other.

The binder or lower section, *b*, is of a size to fit and slide or telescope within the upper section, and is formed with a finished lower

edge, *f*. The upper edge is turned out to 50 form a narrow flange, *g*, to rest upon the flange *e* or lugs *d* of the upper section when the parts are assembled. Notches *h* are cut in the flange *g* to receive the lugs *d*.

To assemble the parts, the section *b* is 55 dropped within the section *a*, and both together are slipped over the bristles and stock, and the section *a* is secured to the stock by small tacks *c*.

When first put into use the bridle is at its 60 full length, as in Fig. 1, the lower section, *b*, being held in place by the outer flange, *g*, resting upon the inner flange, *e*, the lugs *d* entering the notches *h*. When the brush becomes worn sufficiently to render a shorter 65 binding necessary, the lower section is pressed into the upper section until the flange *g* passes the lugs *d*, when it is given a quarter-turn, and is maintained in its retracted position by the flange *g*, resting on the lugs *d*.

My improved bridle above described is not liable to become cut or torn or deteriorated by the action of oils, &c., as are bridles of rubber. It presents a smooth surface, whereby it is easily kept clean, and it has no 75 screws, clamps, nor guides to become clogged, broken, or lost. It permits free play of the bristles down to the stock, and at the same time so effectively protects and preserves them that when the brush is worn close and 80 the bridle is removed to another brush (which may be readily done) the old brush can be continued in use for a considerable length of time. This bridle is, moreover, inexpensive 85 in construction, being readily spun or struck up from sheet metal, or formed in any other desired way.

It is obvious that the material of which the attachment may be made and that the number of telescoping sections and of the supporting-lugs, as well as the shape of the sections, may be varied without departing from the spirit of my invention.

I do not claim the telescopic drinking-cup shown in United States Letters Patent No. 95 28,597, nor the combination, with a brush or its handle, of an extensible tube, as shown in English Patent No. 1,876 of 1881.

I claim—

1. The combination, in a brush-bridle, of a shield-section, *a*, adapted, as described, to be secured to the stock of a brush, with a binder-section, *b*, telescoping within said shield-section, substantially as described.
2. The combination, in a brush-bridle, of a shield-section, *a*, adapted, as described, to be secured to the stock of a brush, and formed *to* with the inner flange, *e*, with a binder-section, *b*, having the outer flange, *g*, telescoping within said shield-section, and means, as de-

scribed, to retain said binder-section in a retracted position, substantially as described.

3. The brush-bridle consisting of a section, *a*, adapted, as described, to be secured to the stock of a brush and having the inner flange, *e*, and lugs *d*, and a section, *b*, having the outer flange, *g*, with notches *h*, substantially as described.

WILLIAM L. BARNES.
